UNITED STATES PATENT OFFICE.

MARY A. PETERS, OF BROOKLYN, NEW YORK.

GUARD FOR BEDS.

1,146,095.

Specification of Letters Patent. Patented July 13, 1915.

Application filed December 27, 1913. Serial No. 809,038.

To all whom it may concern:

Be it known that I, MARY A. PETERS, a citizen of the United States, residing at Brooklyn, in the county of Kings and State 5 of New York, have invented new and useful Improvements in Guards for Beds, of which the following is a specification.

This invention relates to security attachments for bedsteads and the object of the 10 invention is to provide a simple, inexpensive and efficient device adapted to be readily applied to a bed so as to prevent an infant or invalid from falling or crawling off the bed, the device being constructed so as to 15 permit all necessary freedom of movement of the user.

Further objects of the invention will appear as the following description is read in 20 connection with the accompanying drawings forming a part of this application, and in which:

Figure 1 is a perspective view looking 25 down upon the bed, showing the application of the device. Fig. 2 is a sectional view taken through the bed.

Referring more particularly to the drawing, the device is constructed of a long band or strap 1 of any suitable material, one terminal of which is provided with a longitudinally projecting eye member 2 adapted to 30 be engaged by a suitable hook member 3 connected to an intermediate portion of the band or strap upon the same side thereof and arranged nearer the end having the eye 35 member. Immediately adjacent the eye member the band is formed with an eyelet 4 and a similar eyelet 5 is arranged adjacent the hook. The eyelets 4 and 5 are arranged to register with each other so as to receive 40 a fastening device in the form of a safety pin or the like. The opposite terminal of the band or strap is provided with coacting fastening devices, the purpose of which will be hereinafter described.

45 In applying the device the end having the

eye and hook members is wrapped around the body of the infant or invalid and the hook engaged in the eye member so as to produce a body loop 6. The remaining portion of the belt or strap is passed over the 50 bed and engaged around one side rail thereof and where the bed is arranged against a wall, as shown in Fig. 1, this end of the strap is engaged over the side rail adjacent the wall. To prevent disconnection of the 55 eye and hook members a safety pin is preferably passed through the eyelets 4 and 5, as shown in Fig. 2. The loop 6 formed by connecting one terminal to the intermediate portion of the belt, by means of the hook 60 and eye and the safety pin, is of sufficient size to avoid restricting the movement of the user either in turning or rolling from one side of the bed to the other, although when using one strap the body is limited in 65 its movement toward the exposed edge of the bed. Where the bed is positioned away from the wall a second strap of similar character is applied and these body straps effectively prevent falling from the bed at either 70 side thereof.

What I claim is:

In a device of the class described, a strap having a pair of spaced eyelets therein, an eye secured to one end of said strap adjacent one of said eyelets, a hook secured to the same side of the strap adjacent the other eyelet, said eyelets being adapted to register when the above mentioned end of the strap is bent to form a body encircling loop, and 75 means adapted to pass through said eyelets and maintain the said hook and eye in engagement.

In testimony whereof I affix my signature in presence of two witnesses.

MARY A. PETERS.

Witnesses:

Mrs. L. WEIL,
CHARLES PETERS.
